UNITED STATES PATENT OFFICE

JAMES ROBERT HOWARD, OF TULSA, OKLAHOMA

VENTILATOR

Application filed June 4, 1928. Serial No. 282,701.

This invention relates to ventilators and more particularly to those located in the ceilings of rooms or buildings.

A primary object of the invention is to provide a ventilator in which a horizontal circular motion is transformed into a vertical circular motion.

Another object of the invention is to so construct such a ventilator that a maximum air space will be provided with a minimum area occupation by the device.

Still another object is to construct a ventilator which may be used in connection with a lighting fixture to render it as inconspicuous as possible and permit it to be made ornamental if desired.

In carrying out these objects, the invention is susceptible of a wide range of modification without departing from the spirit or sacrificing any of the advantages of the claimed invention; there being shown in the drawings for illustrative purposes a preferred and practical form, in which:

In the accompanying drawings:

Figure 1 represents a plan view of a ventilator constructed in accordance with this invention;

Fig. 2 is a side or edge view thereof, with the supporting structure shown in section;

Fig. 3 is a transverse section taken on the line 3—3 of Fig. 1;

Fig. 4 is a detail sectional view with the ventilator in open position;

Fig. 5 is a similar view taken on the line 5—5 of Fig. 6 with the vanes closed; and

Fig. 6 is a view similar to Fig. 1 with the vanes closed.

The same reference characters indicate corresponding parts in the different figures.

The drawings illustrate the preferred embodiment of the invention for application to the ceiling of a room or building and which is designed to be installed in the center of the room, a hole being cut in the ceiling of a size to accommodate the ventilator. The ventilator comprises a circular plate or frame 1 provided with a plurality of peripherally spaced apertures 2 for attachment of the frame to a suitable support by fastening elements, not shown. A central opening 3 is

provided for passage therethrough of a lighting fixture. Around this opening 3 is an annular frame 5 against which the fixture plate of canopy C is designed to fit firmly without interfering with the operation of the ventilator. If no lights are to be used the central opening is preferably closed by a suitable cover, not shown.

A suitable wire screen 5 is attached to the underside of the ventilator to prevent the entrance of insects.

A plurality of hinged vanes or shutters 6 are arranged radially between the frames 1 and 4, any desired number of which may be employed, sixteen being here shown and which together with the frames may be made of any suitable material and decorated in any desired manner.

Each of the shutters 6 has a right angular laterally extending arm 7 at its outer end which arm is pivoted at its free end to an annular band 8, which we will term the "rotary ring." Chains 10 and 11 are connected with the band 8 and extend through loops 12 and 13 and have hand grips in the form of rings 14 and 15 which are conveniently located so that a pull exerted on one or the other will open or close the shutters 6 either partially or completely according to the pull given. As shown these chains are connected with the band 8 through a pivoted slotted plate 16, said plate being mounted on one of the pivots of an arm 7.

It will thus be seen that by mounting the shutters radially between the two frames 1 and 4 and hingedly connecting them to swing vertically into open or closed position that when closed the free edge of one will overlap the hinged edge of the next as shown clearly in Fig. 5. The arms 7 of the shutters are made of flexible or springy material being either a part of the shutter turned up or a separate strip of spring material attached to the shutter. This springiness of the arms 7 takes care of variations of the radius of the shutters and thus enables the shutters to work smoothly.

It will be obvious that when the band or ring 8 is moved horizontally in a circular direction the pull exerted thereby on the

arms 7 of the shutters will cause the shutters to swing vertically in a circular direction to either open or close them.

Pulleys 17 are preferably located in the loops 12 and 13 and over which the chains are trained to facilitate their movement.

Without further description it is thought that the features and advantages of the invention will be readily apparent to those skilled in the art, and it will, of course, be understood that changes in the form, proportion and minor details of construction may be resorted to, without departing from the spirit of the invention or its scope as claimed.

15 I claim:

1. In a ventilator a frame, a plurality of radially disposed vanes hingedly mounted on the frame for movement towards and away from the latter, a manually operable ring 20 encircling the vanes and having operative connection therewith whereby upon rotation of the ring the vanes will be simultaneously adjusted about their axes, oppositely extending flexible operating elements attached to the ring, and guides attached to the frame through which the flexible elements pass.

2. In a ventilator, a frame, a plurality of radially disposed vanes hinged thereto for movement toward and away from the frame, 25 an arm fixed to each vane and extending at right angles thereto, and a manually operable ring encircling the vanes and having pivotal connection with each arm.

JAMES ROBERT HOWARD.
